[57] **CLAIM**

The ornamental design for a magnetic memory storage
container, as shown and described.

DESCRIPTION

FIG. 1 is a perspective view of a magnetic memory
storage container showing our new design;

FIG. 2 is a top plan view thereof;

FIG. 3 is a cross-sectional view taken through one of
the upstanding tabs in the cover;

FIG. 4 is a right side elevational view thereof;

FIG. 5 is a front elevational view thereof; and,

FIG. 6 is a bottom plan view thereof.

FIG. 1

FIG. 2

FIG. 3

FIG. 4

FIG. 5

FIG. 6
